[57] CLAIM

The ornamental design for a windshield cover, as shown and described.

DESCRIPTION

FIG. 1 is a front elevational view of the windshield cover of the present invention;

FIG. 2 is a rear elevational view of the windshield cover of FIG. 1;

FIG. 3 is a left side elevational view of the windshield cover of FIG. 1;

FIG. 4 is a right side elevational view of the windshield cover of FIG. 1;

FIG. 5 is a top plan view of the windshield cover of FIG. 1; and,

FIG. 6 is a bottom plan view of the windshield cover of FIG. 1.

The straps shown in the FIG. 2-6 drawing views are shown broken away to indicate indeterminate length.
